UNITED STATES PATENT OFFICE

2,509,871

MUSIC ROLL ALARM CLOCK

Fritz Loeffler, New York, N. Y., assignor to Lador, Inc., New York, N. Y., a corporation of New York

Application May 12, 1948, Serial No. 26,692

14 Claims. (Cl. 58—12)

1

This invention has to do with improvements in clock mechanisms and more particularly with clocks having a music roll as an alarm.

Music rolls as such are well known articles of commerce and have previously been used to a limited extent in combination with mechanical (spring) operated alarm clocks. Usually in these clocks there had been separate and independent driving means, e. g. springs, for the clock and the music roll so that two hand winding operations had to be performed. Another shortcoming of these clocks was that the operation of the music roll could not be sufficiently well controlled.

According to my invention a single motor driving means, e. g. an electric motor, operates the clock mechanism as well as the music roll. The present device therefore combines the advantages attendant to an electric clock with those of a clock having a music roll alarm.

According to a feature of my invention I provide a snap acting device which abruptly disengages the music roll from its driving mechanism to insure abrupt stopping of the roll. In this way it is possible accurately to control the operation of the music roll for a predetermined period of time.

According to another feature of my invention, I provide a second more penetrating alarm, like a bell, which may be selectively connected to operate after the music roll has been stopped.

Still another feature of my invention is that I provide a combination hour hand and alarm marker on the face of the clock. Usually a separate indicator is necessary to mark the time at which it is desired for the alarm to operate. I provide in addition to the customary fixed hour dial, an adjustable alarm dial rotating with the hour gear. The alarm time is set by rotating the adjustable dial into alignment with a marker provided on the hour hand.

For a more complete understanding of my invention reference should be had to the following description considered in connection with the drawings.

In the drawings:

Fig. 1 is a side elevation with the outside housing removed;

Fig. 2 is a section of the line 2—2 of Fig. 6;

Fig. 3 is a section on line 3—3 of Fig. 6;

Figs. 4, 4a, 4b and 4c are schematic diagrams showing the operation of the cam followers and the release lever mechanism;

Fig. 5 is a section on the line 5—5 of Fig. 6;

Fig. 6 is a front elevation of the clock with the front housing, dials and front plate removed;

2

Fig. 7 is a front view of the assembled clock;

Fig. 8 is a cross section on the line 8—8 of Fig. 7; and

Fig. 9 is a plan view of the spacer separating the front plate and clock dial.

The clock mechanism or works, resting on a base 9 (Fig. 1) may be inserted as a unit into an opening in the bottom of an outside housing 10. A leaf spring 11 secured to post 12 by screw 13 presses against the back side of housing 10 and prevents rattling of the unit. A crystal 14 is held in place by bezel 15 against the edges of another suitable opening in the side of the housing.

The clock mechanism is driven by a constant speed electric motor 16, preferably of the alternating current synchronous type which is secured by screws (not shown) to back plate 18. The operation of the mechanism about to be described is used to reduce the normal speed of the motor to operate the seconds', minutes' and hours' gears of the clock.

The motor shaft (not shown) of motor 16 carries a pinion 23 which engages a shaft gear 24 mounted with a pinion 25 on a shaft 26. Pinion 25 drives a shaft gear 27 mounted with a pinion 28 on a shaft 29. Pinion 28 drives gear 30 carrying pinion 31 mounted on a shaft 32. Pinion 31 drives a shaft gear 33 mounted with a pinion 34 on center shaft 35. A sweeping second hand 37 is mounted on the outer end of shaft 35. Pinion 34 drives a gear 38 mounted on a pinion shaft 39. A pinion 39' (Fig. 2) forming part of shaft 39 engages a gear 40 which is frictionally held by a spring washer 41 to a minute hub 42 and a pinion 43 pressed on hub 42. Minute hub 42 carries at its outer end a minute hand 44. Pinion 43 engages a gear 45 mounted on a pinion 46 which turns loosely on pinion shaft 39. A collar 47 positions pinion 46 on pinion shaft 39 so that it drives a gear 48 mounted adjacent an end of hour hand hub 49. Hub 49 carries at its outer end an hour hand 50. An alarm gear 51 (Fig. 3) is mounted on alarm hub 52. Alarm cam 53 loosely mounted on hub 49 is coupled to alarm gear 51 by posts 54. On the outer end of alarm hub 52 an adjustable alarm dial 58 is mounted so that it will rotate with the hub 52 but may be displaced with respect thereto. A spring washer 55 is mounted between a flange 56 of hub 52 and a flange 57 of hour hand hub 49. Spring 55 presses flange 57 against alarm cam 53 thereby causing parts 48, 49, 53, 51, 52 to operate in unison.

With the aid of Figs. 4-4c the operation of the device controlling the engagement of the music

alarm to the rest of the clock mechanism will be explained. A release lever 62 positioned between alarm gear 51 and alarm cam 53 is pivotally mounted on a shaft 63. A coiled spring 64, one end of which is fastened to one of posts 54, tends to hold lever 62 in inactive position (Fig. 4) pressing the lever's end 65 against flange 56. Alarm cam 53 has a cut out portion whose edges 66, 67 are substantially perpendicular to one another. Release lever 62 has a radial edge 68 which is slightly displaced with respect to edge 66 of cam 53 and a circular edge 69 in line with the contour of cammed surface so as substantially to cover edge 67 of the cut out when the release lever is in inoperative position.

A locking and follower lever 70 is mounted on a hub 71 (Fig. 3) on a shaft 72 which is rotatably mounted in front and back plates 19, 18. On one end of lever 70 a cam follower 61 is mounted and projects from the lever so as to slide along the cammed surface of cam 53. A spring 73, one end of which is attached to a post 74 and the other end to arm 75 of lever 70, exerts pressure to move cam follower 61 towards alarm cam 53. The other end of lever 70, best shown in Fig. 5, carries a bushing 76 with a short shaft 77. A gear 78 with a hub 78' is rotatably mounted on shaft 77 and is engaged by a gear 79. Gear 79 is mounted on a hub 60 along with a gear 59 which is driven by gear 30 (Fig. 3).

As cam 53 is rotated in clockwise direction, lever 70 will force follower 61 down edge 66 of the cut out portion to the position shown in Fig. 4a, whereupon gear 78 at the other end of lever 70 is swung downwards into engagement with a gear 80 which is connected to a music roll 81 (Fig. 1) and rotates the latter. The musical sound is produced when comb 82 (Fig. 6) is engaged by pins (not shown) projecting from the music roll.

As cam 53 continues to rotate, cam follower 61 rides along edge 67 and engages radial edge 68 of release lever 62 to rotate it about shaft 63 against the pressure of spring 64. When the release lever has been turned to a point greater than the friction angle between it and the cam follower, spring 64 will suddenly snap the release cam 62 back to its inactive or normal position, causing edge 68 to slide past cam follower 61. The normal position of release lever 62 is with its end 65 contacting flange 56. The operation of lever 62 depends on the relative tension of springs 64 and 73. Springs 73 is more resilient than spring 64 so that the pressure of spring 73 will be overcome and gear 78 moved out of contact with gear 80.

Cam follower 61 rides along curved edge 69 of release cam 62 and the cammed surface of 53. When cam follower 61 is lifted out of the cut out portion of cam 53, lever 70 is suddenly swung up so that gear 78 abruptly breaks with music roll gear 80, thus stopping the playing of the music.

As distinguished from the usual gradual disengagement between an alarm and its driving source, I break the connection between music roll gear 80 and gear 78 by means of release lever 62 so fast that music roll 81 comes to a stop almost instantaneously upon the operation of lever 62. The importance of the abrupt disengagement is that the music roll is stopped dead and not gradually. In this connection I have found that in certain cases where the music roll has a great deal of inertia the application of a suitable brake to the roll will prevent any unwanted movements therein.

Fig. 4c shows cam follower 61 just after it has been lifted out of the cut out and as alarm cam 53 continues to rotate, the follower slides around cam 53 until it can once again enter the cut out portion, e. g. 12 hours later.

A second and more penetrating alarm, such as a bell 85, (Fig. 1) is mounted on post 12 by spacer 84 and plate 86. The alarm is sounded by means of an arm 87 which is movably mounted on a cross piece 88 held on pivots 89 between back plate 18 and front plate 19. Arm 87 is under tension from a spring 90 (Fig. 6) fastened to a post 91. At the other end of arm 87 an elbow 94 projects, on one end of which a striker or hammer 95 is provided and from the other end a cam follower 96 projects. A lug 97 projects from arm 87 between hammer 95 and cam follower 96. Cam follower 96 rides around alarm cam 53 close to cam follower 61. The distance between the two cam followers is such that follower 96 can slide past edge 66 of the alarm cam only after follower 61 has been lifted into its inoperative position by the operation of release lever 62. Thus the music alarm must have sounded and stopped before the bell alarm can operate.

The bell alarm operates in the following manner: After follower 96 has dropped into the cut out portion of alarm cam 53, a projection 100 of crosspiece 88 which is connected to spring 90 is moved into engagement with the teeth of a star wheel 101 which rotates with shaft 26. The alternate lifting of arm 87 by the star wheel and retraction by spring 90 causes hammer 95 to strike bell 85 and produce the conventional ringing alarm. As alarm cam 53 continues its rotation, cam follower 96 rides up edge 67 of the cam and the stroke of arm 87 is gradually diminished until follower 96 again reaches the periphery of cam 53, whereupon projection 100 is disengaged from star wheel 101 by the outward movement of arm 87. The bell alarm ceases ringing and will not be operated until the alarm cam 53 makes another complete rotation, i. e. after 12 hours have elapsed.

The operation or non-operation of the alarms is controlled by a shaft 104 (Fig. 6) which extends rearwardly through the housing of the clock and on which a disc 105 having a pin 106 projecting therethrough is pressed. A lever 107 is rotatably mounted on hub 71 and has one end contacting pin 106 on one side of disc 105. Lever arm 75 may contact pin 106 on the other side of disc 105. The other end 108 of lever 107 is adapted to contact projection 97 of arm 87. A spring 110 anchored to post 74 tends to hold lever 107 against pin 106.

Depending on how pin 106 is set (by turning shaft 104) the music alarm will operate (position M), the music alarm and then the bell will operate (position M+B), or both alarms will be silent (position S).

In position M, the bell alarm cannot operate because lever 107 is held by spring 110 against pin 106 so that upper end 108 of lever 107 rests against lug 97 and prevents cam follower 96 from sliding down edge 66 of alarm cam 53. However, lever arm 75 is free of the pin and since lever 70 can still move the music alarm will operate.

If pin 106 is turned counterclockwise to position M+B, both the music and bell alarms will operate because lever 107 is rotated about hub 71 and is pressed by spring 110 against pin 106 so as to raise end 108, as indicated in dotted lines Fig. 6, out of engagement with projection

97. Cam follower 96 may then drop past edge 66 and operate the bell alarm as above described. Since the movement of lever 70 is not influenced by this position of pin 106, the music alarm will operate as before.

If pin 106 is moved clockwise to the position S neither alarm will operate because end 108 of lever 107 holds out the bell alarm as above described. Pin 106 also engages lever arm 75 preventing lever 70 from rotating and cam follower 61 entering the cut out. The music alarm is thereby held out. A flat spring 98 (Fig. 6) suitably fastened to front plate 19 may conveniently be arranged to have a nub in one end register with notches in disc 105 which correspond to positions M, M+B, S. The disc is thereby kept from rotating against the pressure of springs 73 and 110.

The setting of the alarms is controlled by a shaft 114 (Fig. 1) which extends through the rear of the housing. At the front end of shaft 114 a gear 115 is mounted and meshes with a gear 116 rotatably mounted on a stud 117. Gear 116 engages gear 51 which controls the rotation of alarm cam 53 and alarm dial 58. By overcoming the friction of spring 55 against the parts mounted on hubs 49 and 52, the alarm dial can be rotated, and aligned with inner pointer 119 of hour hand 50 (Fig. 7). The novel construction of hour hand 50 enables it to serve a dual purpose—to indicate the hour of the day as well as the time to which the alarm is set. Hand 50 is formed intermediate its ends into a ring 118. Within this ring small pointer 119 may be aligned with suitable numbers on the adjustable alarm dial. Outer pointer 120 indicates the hours of the day in the usual manner.

The hands of the clock are set by rotation of a shaft 122 (Fig. 2) which extends through the rear of the housing. When a gear 123 pressed on shaft 122 is rotated the friction between gear 40 and pinion 43 created by spring washer 41 is overcome and the hands moved.

The music roll 81 is supported in a frame 124 by screws 125 (Fig. 1). A locating screw 125' locates gear 80 with respect to gear 78. Frame 124 is fastened to front plate 19 by screws 130.

Referring to Fig. 8, a spacer 126 separates front plate 19 from clock dial 127. A circular opening is provided in clock dial 127 in which alarm dial 58 is placed. The alarm dial is practically flush with clock dial 127. The clock dial is positioned on extensions 128 of post 17 and the distance from posts 17 to center shaft 35 is accurately measured. Since the clock dial will be rigidly held it is possible to have only a small clearance between the two dials. The face of the clock has a neat and compact appearance.

Since shafts 26 and 29 are the most directly coupled to the motor shaft they rotate at relatively high speeds and should be lubricated and for that purpose I provide holes 131 and 132 in spacer 126 (Fig. 9). When clock dial 127 is in place, two chambers defined by holes 131 and 132 are provided between the dial and front plate 19 into which lubricating means, such as a wick, may be placed continuously to lubricate the shafts. A clearance hole 133 may also be provided in spacer 126 to permit pivots 89 to project from front plate 19.

While I have disclosed one embodiment of my invention it will be clear to those skilled in the art that various modifications may be made thereon and that certain features thereof may be used separately or in other combination without

departing from the scope of my invention as set forth in the appended claims.

What is claimed is:

1. A clock comprising a clock mechanism, a music roll, and a single driving means connected with the clock mechanism for driving it and connectable to drive the music roll, coupling means for operatively connecting the music roll to said driving means, and means operable at predetermined times by the clock mechanism for actuating the coupling means.

2. A clock comprising a clock mechanism, a music roll, a single driving means for driving both the clock mechanism and the music roll, means for operatively connecting the music roll with said driving means and means including a spring and lever means for controlling the connection between said driving means and roll.

3. In combination with a clock mechanism, a constant speed motor for driving said mechanism, a music roll alarm, means for operatively connecting the music roll with said motor, and lever means for abruptly making and breaking the connection between the motor and music roll.

4. The device according to claim 3, a second alarm and means for operatively connecting said second alarm with said motor.

5. The device according to claim 4, and means for connecting said second alarm after the breaking of the connection with the music roll.

6. In an alarm clock housing, clock works, an alternating current motor for driving said works, a music roll, means for operatively connecting said roll to the motor, a cam having a follower controlling the operative connection of the motor to the music roll, and a spring operated release lever for moving the cam follower with respect to the cam to disconnect abruptly the motor from the music roll.

7. The device according to claim 6, and means projecting through said housing for preparing the control of the music roll by the cam at preset times.

8. The device according to claim 6, a bell alarm, an arm extending from bell alarm, means for connecting said arm to the motor, a second cam follower for controlling the operative connection of said arm to the motor, said second follower being displaced with respect to said first follower so that the music roll will operate before the bell.

9. The device according to claim 6, and means for resiliently mounting within the housing said clock works, motor, cam, cam follower and lever as a unit.

10. In an alarm clock, an alternating current motor for driving the clock, a cam rotated by said motor, a music roll, means for connecting the music roll to the motor, a first cam follower for controlling the said last-mentioned means, a bell, a hammer for striking said bell, a second cam follower for controlling the operation of the hammer to strike the bell, a snap acting release lever rotatably mounted on said cam and engaged at one end by said first cam follower, and a spring fastened to the other end of the lever whereby the lever will abruptly break the connection between said first follower and the cam.

11. In an alarm clock, an alternating current motor for driving the clock mechanism, a cam having a cut out portion and rotated by the motor, a first cam follower contacting said cam, a music roll connected to said follower operable upon the follower moving into said cut out portion, a second cam follower contacting said cam, a bell alarm connected to said second follower and operable

upon the follower moving into the cut out portion of the cam, a release lever having a normal position mounted on said cam adjacent its cut out and contacting said first follower upon its entering the cut out, and means for quickly returning said lever to normal position thereby moving said first follower out of the cut out and stopping the operation of the music roll alarm.

12. In an alarm clock, an alternating current motor for driving the clock mechanism, an hour hand, a gear for rotating said hour hand, a cam having a cut out portion and connected to said gear, a first cam follower contacting said cam, a music roll connected to said follower operable upon the follower moving into said cut out portion, a second cam follower contacting said cam at a point behind said first follower with respect to the direction of rotation of the cam, a bell, a striker connected to said second follower and operable upon the second follower moving into the cut out portion of the cam to strike the bell, a snap acting release lever having a normal position mounted on said cam adjacent the cut out but displaced with respect to the cut out so that said followers may enter it, a spring fastened to one end of the lever for quickly returning said lever to normal position thereby moving the first follower out of the cut out and stopping the operation of the music roll, and means for alternatively connecting the music roll, the music roll and bell striker or disconnecting the music roll and bell striker to the clock mechanism.

13. In an alarm clock, an alternating current motor for driving the clock mechanism, a stationary clock dial having a central opening, an adjustable alarm dial situated in said opening and in substantially the same plane as the clock dial, an hour hand, a gear for rotating said hour hand, a cam having a cut out portion and connected to said gear, a first cam follower contacting said cam, a music roll connected to said follower operable upon the follower moving into said cut out portion, a second cam follower contacting said cam at a point behind said first follower with respect to the direction of rotation of the cam, 45

5 a bell, a striker connected to said second follower and operable upon said second follower moving into the cut out portion of the cam to strike the bell, a snap acting release lever having a normal position mounted on said cam adjacent the cut out but displaced with respect to the cut out so that said followers may enter it, said lever having a surface for contacting said first follower, a spring fastened to one end of the lever for quickly returning the lever to normal position thereby moving said first follower out of the cut out and stopping the operation of the music roll, a disc having a pin projecting therefrom movable into three positions, in the first of said positions 10 the music roll and bell striker being both disconnected from the clock mechanism, in the second position only the music roll being connected, and in the third position the music roll and bell striker being both connected, a projection from the first 15 cam follower contacting the pin only in said first position whereby said first follower is held free of the music roll, and a second lever positioned so that one end engages the second cam follower and the other end said pin in said first and second 20 positions of the pin whereby said second follower may be held from entering said cut out to prevent operation of the bell alarm.

14. The device according to claim 13, and in which said hour hand is formed into a ring intermediate its ends, and has a pointer within said 25 ring for alignment with said alarm dial.
